UNITED STATES PATENT OFFICE.

WILLIAM P. BETTENDORF, OF BETTENDORF, IOWA; J. W. BETTENDORF ADMINISTRATOR OF SAID WILLIAM P. BETTENDORF, DECEASED.

UNDERFRAME FOR DUMPING-CARS.

1,039,638.

Specification of Letters Patent. Patented Sept. 24, 1912.

Application filed March 5, 1910. Serial No. 547,569.

To all whom it may concern:

Be it known that I, WILLIAM P. BETTENDORF, a citizen of the United States, residing at Bettendorf, in the county of Scott and State of Iowa, have invented new and useful Improvements in Underframes for Dumping-Cars, of which the following is a full, clear, and exact description.

My invention relates to the underframes of dumping cars, and particularly to that type of dumping cars, whose bodies are adapted to be lifted from their trucks.

The objects of my invention are to provide such a construction of the body-bolsters that the tilting of the car-body can be accomplished without affecting the relation of the body-bolster to the truck-bolster, and so that when tilted the body will be maintained in its tilted position by the automatic action of a jointed strut or brace, and so that when this brace is "broken", and the car resumes its normal vertical position, it will be maintained and locked in said position by hooks that automatically engage the ends of the cradle-part of the body-bolster. This I accomplish by the means hereinafter described and as particularly pointed out in the claims:

In the drawings:—Figure 1 is a plan view of the underside of one half of a dump car embodying my invention. Fig 2 is a transverse vertical section taken on dotted line 2, 2, Fig. 1. Fig. 3 is a view similar to Fig 2 showing the car in its tilted position. Fig 4 is an end view of said car illustrating the means for manipulating the jointed braces, and the hooks, for maintaining the car in its tilted position, or in its horizontal position. Fig. 5 is a bottom plan view of the underframe. Fig. 6 is a view similar to Fig. 2 showing the car converted to a "rigid" body.

In the drawings A, A, represent Z-bar side-sills; B, B, center-sills, and C the end-sills. The end-sills are, preferably, made of cast metal, and the central portion of its inner side extends, in the horizontal plane of the floor of the car, inward toward the body-bolster, to a point about midway between the transverse plane of the pivot of the truck and the end of the car, and its rear edge portion is provided with a depressed seat in which the lower flanges of the center-sills are seated and suitably secured so that

their upper surfaces are in the same plane 55 as the upper surface of said extension c.

The body-bolster comprises two parts, which may be the bolster proper and the "cradle". The bolster consists, preferably, of a transverse cast metal beam extending from side-sill to side-sill of the car, the central part of which is rectangular in cross section and tubular and the portions between this central part and its ends are channeled and the lower edges of the side-walls of said channeled portions are flanged inward. The top of this bolster "proper" consists of a flat upper plate, D, the upper surface of which is in the same horizontal plane as the upper surface of the upper flanges of the center-sills and side-sills, and the lower portion thereof has its parallel side-walls d separated a distance less than the width of said top-plate, D, and is bellied downward so that the depth thereof is greatest at its 75 center of length and so that the lower side thereof is curved to enable it to rock from one side to the other on its lower edges. The lower side edges of said bolster are provided with recesses E, which are, preferably, arranged in pairs in the same transverse plane, and so that the pairs will be equal distances apart. The center of length of the upper portion of this bolster is provided with a suitable transverse depressed seat f 85 of sufficient dimensions to permit the passage of the center-sills, that is of such depth that the upper surfaces of the upper flanges of said sills will be in the same horizontal plane as the upper surface of the bolster. 90

The ends of the bolster are seated upon the inturned lower flanges of the Z-bar side-sills, and are suitably secured thereto by rivets or otherwise, and the floor G of the car, which consists, preferably, of a single sheet metal plate, extending from end to end and side to side of the car, is riveted to the center-sills, the side-sills and bolsters of the underframe.

The bolster rests upon and is seated in a cradle consisting of a transverse channeled beam H, the bottom plate or web of which extends in a straight horizontal plane from end to end, and is provided at the inner angles of the lower flanged edges of its side-walls with profuberances that constitute teeth or cogs g that are adapted to be engaged by the recesses E in the lower edges 100 105

of the bolster. I prefer to arrange these cogs *g* and recesses *E* so that there will be one at the center of length of the bolster in the longitudinal plane of the king-bolt 5 of the truck, and an equal number between the same and the ends of the bolster. Thus, when the car is in its normal vertical position the central cogs and recesses will be in engagement, and when the car is tilted the 10 engagement of said cogs and recesses will prevent the car-body from slipping upon said cradle *H* and thus injure their proper relation. At its center of length the cradle has a suitable male center-bearing *e* made 15 integral with and depending from its under surface that is adapted to engage a suitable female bearing of any of the usual types of car-trucks.

The car-body is tilted in one direction or 20 the other by means of longitudinal rock-shafts *a*, one near each side of the car, and their ends are journaled in suitable bearings in the end-sills and bolsters of the car. They extend through suitable openings in the bolster proper near the top of the same, and one has a handle or lever *b* on its outer 25 end at one end of the car with which to rock it, and the other shaft has a handle on its opposite end. Each shaft has mechanism adjacent to the bolster located nearest the end thereof on which the handle is mounted, by means of which the tilting is done. This mechanism is the same for both 30 shafts, and the following description applies to each. Immediately next where said shaft *a* passes through the bolster proper, it is provided with a short arm *h*, the end of which has a link *I*, pivotally connected thereto, which latter extends along the side 35 of the adjacent side-wall of the bolster toward the center of the car, and has its opposite end suitably enlarged and provided with a slot *j* therein extending oblique to the length of the plate. On the inside of the 40 bolster, that is, between the side-walls thereof, I mount the upper end of the upper member, of a toggle or jointed brace, *J* on a longitudinal pivotal shaft *x* that extends 45 from bolster to bolster and has its ends journaled therein. The lower end of the 50 lower member, *J'*, of said toggle is pivotally secured to the bottom of the cradle at a point slightly farther from the center of width of the car than is the point of connection of the upper member, *J*, with the 55 bolster. The upper member, *J*, of this brace is provided with a laterally projecting arm *k* that extends out through a segmental slot *K* in the side-wall of the bolster alongside 60 of which link *I* is placed, and extends through the diagonal slot, *j*, in the adjacent end of said link *I* and has its extremity provided with suitable means for maintaining 65 its connection with said link. When the car is tilted to one side the brace on the

opposite side of the center of the bolster will straighten out, and its knee-joint will move slightly beyond the dead center, at which point it will be held by the arm *k* of the upper member, *J*, engaging the lower limit of the diagonal slot *j* of the link *I*, and prop up the raised side of the car. When it is desired to restore the car to its normal horizontal position, shaft *a* is rocked so that arm *h* pulls link *I* toward the adjacent side of the car; and the latter, pulling on the upper member of the brace, moves it outward and breaks the joint, and the weight of the car causes it to gravitate to its normal vertical position. When rock-shaft *a* is thus moved, the brace breaks and doubles into the position shown in Fig. 2 of the drawings.

Should it be desired to maintain the body of the car permanently in a vertical position, the lower member *J'* of the brace may be removed, and the lower end of the upper member *J* have its lower end secured to the former pivotal lug of the lower member, and the hooks *L* removed, substantially as shown in Fig. 6 of the drawings.

When the car-body is in its normal position, with its floor horizontal, it is held by means of depending hooks, *L*, the upper ends of the straight shanks of which are secured to shaft *a*, mediate the side-walls of the bolster, and the lower hooked ends catch under the ends of the bottom web of the cradle. Near the shaft *a* the shank of each of these hooks has a tray *m* projecting therefrom toward the adjacent end of the bolster, and a coil-spring *M* is interposed between each tray and the respective bolster thus keeping the hooks in engagement with the ends of the cradle.

What I claim as new is:—

1. An underframe for cars comprising side-sills, center-sill, end-sills, integral bolsters extending from side-sill to side-sill having a depression in their upper central portions, and their undersides curved like a rocker, and a horizontally disposed channeled cradle in which said bolster is seated.

2. An underframe for cars comprising side-sills, center-sill, end-sills, integral bolsters supported by said side-sills having their undersides curved like a rocker, and transverse horizontally disposed channeled cradles in which said bolsters are seated, each having a center-bearing plate on its underside.

3. The combination with a suitable truck-bolster of an underframe for cars comprising side-sills, center-sill, end-sills, integral bolsters having their undersides curved like a rocker, and transversely disposed integral flat cradles in which said bolsters are seated, having integral center bearing plates on their undersides.

4. An underframe for cars comprising

- side-sills, center-sill, end-sills, integral bolsters each having their undersides curved like a rocker, and transversely disposed channeled cradles in which said bolsters are seated, each having a center bearing plate on their undersides.
5. An underframe for cars comprising side-sills, center-sill, end-sills, integral bolsters extending from side-sill to side-sill and having their upper central portions recessed to permit the passage of the center-sill, and having their undersides curved like a rocker, and integral cradles each having a flat longitudinal surface and center-bearing depending from the underside thereof, in combination with a car-truck and bolsters thereof having bearings with which said center-bearings engage.
6. An underframe for cars comprising side-sills, center-sill, end-sills, integral bolsters having their undersides curved like a rocker and having recesses in their under-edges, transversely disposed flat channeled cradles in which said bolsters are seated, each having a center bearing plate on its underside, and having protuberances in its channel that are adapted to engage said recesses.
7. An underframe for cars comprising side-sills, center-sill, end-sills, integral bolsters secured to and extending from side-sill to side-sill and each having its underside curved longitudinally like a rocker, channeled cradles arranged under, extending in the same plane as, and supporting said bolsters, and each having a center bearing depending from their undersides, and braces connecting said bolsters and cradles at points on either side of the center of length of the same.
8. An underframe for cars comprising side-sills, center-sill, end-sills, integral bolsters secured to and extending from side-sill to side-sill and having their undersides curved longitudinally like a rocker and their under edges flanged inward and provided with recesses, cradles arranged under, extending in the same plane as, and supporting said bolsters, and having center-bearings depending from their undersides, and braces connecting said bolsters and cradles at points on either side of the center of length of the same, in combination with a car-truck and bolsters thereof having bearings with which said center-bearings engage.
9. An underframe for cars comprising side-sills, center-sill, end-sills, integral bolsters secured to and extending from side-sill to side-sill and having their undersides curved longitudinally like a rocker, channeled cradles arranged under, extending in the same plane as and supporting said bolsters, and having a center-bearing depend-
- ing from their undersides, and jointed braces connecting said bolsters and cradles at points on either side of the center of length of the same.
10. An underframe for cars comprising side-sills, center-sill, end-sills, integral bolsters secured to and extending from side-sill to side-sill and having their undersides curved longitudinally like a rocker and their under edges flanged inward and provided with recesses, cradles arranged under, extending in the same plane as and supporting said bolster; having protuberances adapted to engage said recesses, and having center-bearing depending from their undersides and jointed braces connecting said bolsters and cradles at points on either side of the center of length of the same, in combination with a car-truck the bolsters of which have bearings that are engaged by said center-bearings.
11. An underframe for cars comprising side-sills, center-sill, end-sills, integral bolsters secured to and extending from side-sill to side-sill and having their undersides curved longitudinally like a rocker, channeled cradles arranged under, extending in the same plane as, and supporting said bolster, and having a center-bearing depending from its underside, braces connecting said bolsters and cradles at points on either side of the center of length of the same, and hooks depending from said underframe that engage said cradles when the car-body is in an upright position.
12. An underframe for dump-cars comprising side-sills, center-sill, end-sills, integral body-bolsters secured to and extending from side-sill to side-sill, cradles for said bolsters that are always in the same vertical plane with said bolsters, and hooks depending from said body-bolsters that engage said cradles when said underframe is in normal position.
13. An underframe for dump-cars comprising side-sills, center-sill, end-sills, integral body-bolsters secured to and extending from side-sill to side-sill, cradles for said bolsters that are always in the same vertical plane with said bolsters, truck-bolsters on which said cradles are swiveled, and hooks depending from said body-bolsters that automatically engage said cradles when said underframe is in normal position.
14. An underframe for cars comprising side-sills, center-sill, end-sills, integral bolsters secured to and extending from side-sill to side-sill and cradles therefor, longitudinal shafts journaled in said underframe, and hooks depending from said shafts and adapted to engage said cradles when said underframe is in normal position.
15. An underframe for cars comprising side-sills, center-sill, end-sills, integral bolsters secured to and extending from side-

sill to side-sill and having their undersides curved longitudinally like a rocker, cradles for supporting the same, jointed braces connecting said bolsters and cradles on each 5 side of the centers of length thereof, longitudinal rock-shafts journaled in said under-frame, and means actuated by said shaft for upsetting said braces.

16. An underframe for cars comprising 10 side-sills, center-sill, end-sills, integral bolsters secured to and extending from side-sill to side-sill and having their undersides curved longitudinally like a rocker, cradles for supporting the same, jointed braces connecting said bolsters and cradles, longitudinal rock-shafts journaled in said under-frame, hooks mounted on said shafts and adapted to engage said cradles when the 15 car-body is in its upright position, and 20 means actuated by said shaft for upsetting said braces.

17. An underframe for cars comprising side-sills, center-sill, end-sills, integral bolsters secured to and extending from side-sill to side-sill and having their undersides curved longitudinally like a rocker, cradles for supporting the same, jointed braces connecting said bolsters and cradles, longitudinal rock-shafts journaled in said under-frame, and links pivotally secured at one 25 end to arms projecting from said shafts for upsetting said braces.

18. An underframe for cars comprising side-sills, center-sill, end-sills, integral bolsters secured to and extending from side-sill to side-sill, and having their undersides curved longitudinally like a rocker, and having the central portions of their upper surface recessed to permit the passage of said 35 center-sill, cradles arranged under, extending in the same plane as, and supporting said bolsters and having center-bearings depending from their undersides and braces connecting said bolsters and cradles at points 40 on either side of the centers of length of the 45 same.

19. An underframe for cars comprising side-sills, center-sill, end-sills, integral bolsters secured to and extending from side-sill 50 to side-sill and having their undersides curved longitudinally like a rocker, and having their under edges flanged inward and provided with recesses, the central portions of their upper surfaces recessed to permit 55 the passage of said center-sill, cradles arranged under, extending in the same plane

as, and supporting said bolsters having protuberances adapted to engage said recesses, and having center-bearings depending from their undersides and braces connecting said 60 bolsters and cradles at points on either side of the center of length of the same.

20. An underframe for cars comprising side-sills, center-sill, end-sills, integral bolsters secured to and extending from side-sill to side-sill and having their undersides curved longitudinally like a rocker, and the central portions of their upper surfaces recessed to permit the passage of said center-sill, cradles arranged under, extending in 70 the same plane as and supporting said bolsters, and having center bearings depending from their undersides, braces connecting said bolsters and cradles at points on either side of the centers of length of the same, and 75 hooks depending from said underframe that engage said cradles when the car-body is in an upright position.

21. An underframe for cars comprising side-sills, center-sill, end-sills, integral bolsters secured to and extending from side-sill to side-sill and having their undersides curved longitudinally like a rocker, and the central portion of their upper surfaces recessed to permit the passage of said center-sill, cradles for supporting the same, jointed 80 braces connecting said bolsters and cradles, longitudinal rock-shafts journaled in said underframe, and means actuated by said 85 shafts for upsetting said braces. 90

22. An underframe for cars comprising side-sills, center-sill, end-sills, integral bolsters secured to and extending from side-sill to side-sill and having their undersides curved longitudinally like a rocker, and the central portions of their upper surfaces recessed to permit the passage of said center-sill, cradles for supporting the same, jointed braces connecting said bolsters and cradles, longitudinal rock-shafts journaled in said 95 underframe, hooks mounted on said shafts and adapted to engage said cradles when the car-body is in its upright position, and means actuated by said shafts for upsetting said braces. 100

In witness whereof I have hereunto set my hand and seal this 2nd day of March 1910.
